[57] CLAIM

The ornamental design for a water-ski handle, substantially as shown.

DESCRIPTION

FIG. 1 is a perspective view of the water-ski handle; FIG. 2 is a side elevation view of one side of the water-ski handle shown in FIG. 1;

FIG. 3 is a top elevation view;

FIG. 4 is a front elevation view;

FIG. 5 is a rear elevation view;

FIG. 6 is a side elevation view of the other side of the water-ski handle not shown in FIG. 2; and

FIG. 7 is a bottom elevation view.
